CARD NO. 6.

UNITED STATES PATENT OFFICE

WILLIAM H. HALL, OF CLYDE, ILLINOIS.

CALENDAR FRAME AND CARD.

No. 909,291.

Specification of Letters Patent.

Patented Jan. 12, 1909.

Application filed February 24, 1908. Serial No. 417,459.

To all whom it may concern:

Be it known that I, WILLIAM H. HALL, a citizen of the United States, residing at Clyde, in the county of Cook and State of Illinois, 5 have invented certain new and useful Improvements in Calendar Frames and Cards, of which the following is a specification.

This invention relates more especially to an improved calendar frame which is particularly adapted to display a system of calendar cards whereby dates covering a large 10 range of years can be readily ascertained.

The primary object of my invention is to construct a calendar frame in such manner 15 that the calendar cards can be easily inserted therein and withdrawn therefrom without injuring or soiling the calendar cards.

Another object is to provide a system of 20 calendar cards covering a large range of years together with the respective months thereof, as well as means whereby a particular date may be readily ascertained.

The invention consists in the features of 25 construction and combination of parts hereinafter described and claimed.

In the drawings, Figure 1 is a front view of the calendar and calendar frame as used; Fig. 2 a transverse section taken on line 2—2 of Fig. 1; Fig. 3 a transverse section taken on 30 line 3—3 of Fig. 1; Fig. 4 a front view of one of the year cards for 31-day months; Fig. 5 a reverse view of Fig. 4; Fig. 6 a front view of one of the year cards for 30-day months; Fig. 7 a reverse view of Fig. 6; Fig. 8 a front 35 view of a calendar card having 31 days, the same being one of a series of similar cards; Fig. 9 a reverse view of Fig. 8; Fig. 10 a front view of another calendar card of the series; and Fig. 11 a reverse view of Fig. 10.

40 My improved calendar frame consists, preferably, of an intermediate piece of matting 12, having usually a strip of card board 13 on its front side. Upon and over this card board 13 is placed a leatheroid or other suitable facing 14, which has its edges bent over and back of the piece of matting 12, and is glued or otherwise secured thereto. An opening 15 is formed in the matting 12, extending through 45 to its outer edge, forming a pocket into which the calendar cards 16 may be inserted; and the strip of card board 13 and the leatheroid or other suitable facing 14 have a square opening through which the calendar cards 16 are displayed. Upon the rear side of the 50 intermediate piece of matting 12 is a back 17 of substantially stiff material, such as tin,

which has, upon its outer side, a suitable covering 18. An elongated slot 19 is punched through the backing 17 and covering 18, so as to enable the various calendar cards to be 60 readily handled from either or both sides of the calendar frame. All of the respective parts of the calendar frame, heretofore described, have the same general design so as to present a thoroughly uniform and harmonious 65 appearance.

Upon the back of the calendar frame, and near its upper edge, is hinged a supporting arm 20, which is adapted to maintain the calendar frame in proper position. A retainer 21 is connected with both the hinged supporting arm 20 and the back of the calendar frame, as indicated in Fig. 2, for the purpose of limiting the outward movement of 70 said arm.

The calendar system preferably employed in connection with the use of this calendar frame consists of cards having a table of years in combination with cards having the various months printed thereon. The 31-day 75 months have a common color or other similar designating means, as well as the 30-day months, and the month of February. In the present instance there are three cards which have tables of years thereon, two 80 months being printed on each side thereof, as shown. The year tables are divided into seven different sections, one for each day of the week, and each card has its sections numbered from 1 to 7, respectively. The year 85 tables, at the bottom of the cards, are for the month indicated above, as in Figs. 4, 5, 6 and 7.

The days of the month are displayed from 90 six different cards, having on both sides the respective calendar months, all of the 31-day months conforming, in color or other common designating means, with the year tables for those months. The same is true as to the 30-day months, and the month of February. 95 It will be understood that the card having year tables is inserted back of the card having the days of the months, as shown in Fig. 1.

Referring now to Figs. 8, 9, 10 and 11, it 100 will be seen that a rectangular opening 22 is punched in each of the cards having the days of the month thereon, said openings being directly below the respective columns of numerals and are also of a size corresponding 105 with the sections of the year cards, as in Fig. 1. In the present system, the various sec-

tions of the 31-day months are numbered from left to right and the 30-day months are numbered from right to left, so that when the card shown in Fig. 8 is reversed, as in Fig. 9, 5 the rectangular opening 22 will appear under the last column of numerals for Saturday, and as the marking of the 30-day months is reversed from that of the 31-day months the same will appear under section No. 1. The 10 same applies to the other cards having the days of the months printed thereon, as in Figs. 10 and 11, in which the rectangular opening 22 is under the second column of numerals for the 31-day months; and, when 15 reversed, is under the sixth column of numerals for the 30-day months, said cards being numbered 2, respectively, because, as stated before, the 30-day cards are read in the opposite direction from those of the 31-day cards.

20 When it is desired to find a particular date, such, for instance, as December 1, 1903, you first take the calendar card for December having the table of years thereon, and, having found the particular year desired in one 25 of the seven columns near the bottom of the card, you proceed to find the calendar card having 31 days, as well as an opening which registers exactly with the particular section of years desired. When this is accomplished 30 you have the correct calendar table, so that, as indicated in Fig. 1, you may know that December 1, 1903, was on Tuesday. As the same procedure applies to the various cards of this calendar system, further explanation 35 is deemed unnecessary.

From the foregoing description it is apparent that my improved calendar frame is constructed in such a manner that the calendar cards can be easily and without difficulty inserted or withdrawn, by reason of the fact 40 that openings are provided through the front and rear of the frame. Although any suitable calendar cards may be used in connection with this frame, the card system heretofore described is especially adapted to be 45 used in connection therewith, because it not only serves for the every day use of the ordinary commercial calendar, but a further advantage lies in the fact that, as before stated, 50 a particular date, covering a large range of years, can be readily found when desired.

What I claim as new and desire to secure by Letters Patent is:

1. In combination with a calendar frame, 55 a series of cards having the months of the years printed thereon and seven sections of a table of years, the sections being numbered from 1 to 7, the numbers reading from left to right on the 31-day months and from right to 60 left on the 30-day months, seven cards having the months of the year printed thereon, each card having an opening formed in a section corresponding to one of the sections of the first mentioned cards, all of the seven

cards having openings in different sections 65 from one another, said opening in each card being adapted to register with one of the seven sections of the year card, substantially as described.

2. In combination with a calendar having 70 an opening in both its front and rear sides, a series of cards having the months of the years printed thereon and seven sections of a table of years, the sections being numbered from 1 to 7, the numbers reading from left to right 75 on the 31-day months and from right to left on the 30-day months, seven cards having the months of the year printed thereon, each card having an opening formed in a section corresponding to one of the sections of the 80 first mentioned cards, all of the seven cards having openings in different sections from one another, said opening in each card being adapted to register with one of the seven sections of the year card, substantially as 85 described.

3. In combination with a calendar frame, 90 a series of cards having the months of the years printed thereon and seven sections of a table of years, the sections being numbered from 1 to 7, the numbers reading from left to right on the 31-day months and from right to left on the 30-day months, seven cards having the months of the year printed thereon, each card having an opening formed in a section 95 corresponding to one of the sections of the first mentioned cards, all of the seven cards having openings in different sections from one another, said opening in each card being adapted to register with one of the 100 seven sections of the year card, the respective cards, when properly adjusted, being adapted to display a common distinguishing mark, substantially as described.

4. In combination with a calendar having 105 an opening in both its front and rear sides, a series of cards having the months of the years printed thereon and seven sections of a table of years, the sections being numbered from 1 to 7, the numbers reading from left to right 110 on the 31-day months and from right to left on the 30-day months, seven cards having the months of the year printed thereon, each card having an opening formed in a section corresponding to one of the sections of the 115 first mentioned cards, all of the seven cards having openings in different sections from one another, said opening in each card being adapted to register with one of the seven sections of the year card, the respective cards, 120 when properly adjusted, being adapted to display a common distinguishing mark, substantially as described.
